VEHICLE AND PARTICULARLY RAILWAY
ROLLING STOCK

William E. Woodard, Forest Hills, N. Y.

Application January 10, 1936, Serial No. 58,505

31 Claims. (CL 105—183)

This invention relates to the structure and operation of vehicles and particularly of railway rolling stock, and especially contemplates improvements in the running gear and the support of the superstructure thereon.

While the invention, at least as to certain aspects and fundamental features, is broadly applicable to vehicles of various types, and to railway rolling stock in general, it is particularly useful in light-weight high-speed rail cars; and it is as applied to that particular type of equipment that I have herein described and illustrated the invention. Furthermore, while the invention involves generally the running gear of such a vehicle and the association of such running gear with any frame or rigid weight carrying structure of such a vehicle, it also has certain special, and especially advantageous, characteristics and relationships peculiar to truck structures and truck frames for such vehicles. Therefore, while not limited in certain aspects, to application to truck structures only, the invention is described and illustrated herein as so applied.

One of the primary purposes of the invention is the reduction of weight of the vehicle generally; and more particularly of the trucks thereof, and still more specifically the reduction of the load per axle.

Another fundamental purpose of the invention is to improve the riding and tracking qualities of high-speed vehicles, and more particularly to provide an extremely flexible truck and wheel arrangement, while maintaining adequate strength and rigidity of the truck frame, and assuring proper guiding and tracking action of the wheels on the rails, even under extremely high-speed operation, and without undesirable motions, vibrations, or synchronous oscillations.

The invention further contemplates reduction of noise in the running gear of high-speed rail equipment; improvement in operation, and extension of the field of usefulness of resilient or pneumatic-tired wheels for such vehicles; increasing the safety of such high-speed rolling stock including reduction of the possibility of derailment; and, in general, the improvement of the construction and operation of rubber-tired railway vehicle trucks, and the reduction of costs, such as initial cost, repairs, replacements, maintenance, etc.

More specifically, the invention contemplates the lightening of the weight of vehicle framing, and particularly of truck frame structures; the reduction of tire and flange loads per wheel, not only by such reduction of weight, but also by in-

creasing the number of wheels supporting the frame, particularly when employed in truck structures, incidental to which also is a substantial elimination of the risk of rubber-tired wheels riding up and off of the rails and a material reduction in the wear of the rubber tires, when such are employed; the improvement of guiding and tracking operation and riding qualities, particularly of such trucks, specifically by the dividing of the wheels into groups which groups are equalized together, the wheels of each group being further equalized together independently of the wheels of another group in the truck; the utilization of a single equalizing system to serve commonly a plurality of functions, including two or more of the following: vertical equalization, lateral equalization, positioning of the wheels and axles longitudinally of the truck, transmission to and equalization of the weight between a plurality of axles, mounting of the wheels and axles in the frame, cushioning the transmission of the weight, centering the wheels laterally, damping vibrations and cushioning shocks both vertically and laterally; and, in general, the provision of flexibility of truck action while at the same time maintaining the rigidity and stability of the truck frame, yielding support of the car body by the frame, and suitable swiveling and limited lateral motion relatively between the truck frame and the vehicle frame.

Still other and more detailed features, objects, and advantages involved in or flowing from the present invention, will appear as the description proceeds; and all such objects and advantages, together with such others as may occur to those skilled in the art, will be clearly understood by reference to the drawings, in which—

Figure 1 is a somewhat diagrammatic outline, in plan, of an eight-wheel truck incorporating the invention, here shown as embodying pneumatic-tired wheels (although it will be understood that the invention is not so limited) and illustrating certain characteristics of operation of the truck upon a curved section of track;

Figure 2 is a top plan view of the truck frame, in some detail, (with parts broken away and shown in section at different levels) and illustrating certain of the equalizing, centering, and cushioning features of the invention, some other parts being omitted, for the sake of clarity;

Figure 3 is a side elevational view of the mechanism of Figure 2;

Figure 4 is an end elevational view, on a somewhat larger scale, of certain of the truck parts of Figures 2 and 3, particularly of the lateral

shock absorbing means and its association with an axle, certain other parts being omitted;

Figure 5 is a fragmentary side elevational view of the left-hand portion of the structure of Figure 3, drawn to a larger scale, particularly illustrating the general arrangement of one group of wheels, equalizing mechanism, and vertical shock absorbing means;

Figure 6 is substantially a transverse vertical section through the mid-portion of the truck of Figure 3, with certain parts shown in elevation and other parts omitted;

Figure 7 is a front elevational view of part of the equalizer centering mechanism (which is shown generally in top plan in Figure 2);

Figure 8 is an end elevational view of Figure 7, and illustrating the securing of said mechanism to a portion of the truck frame;

Figure 9 is a top plan detail of an equalizer member, on a scale larger than that of Figure 2.

Figure 10 is a side elevation of the same;

Figure 11 is a vertical sectional view, taken in a plane transversely of the truck, through one end of the mechanism of Figure 7, showing on an enlarged scale, the details of that device;

Figure 12 is an enlarged vertical sectional view, taken on a plane generally longitudinally of the truck, through the equalizer mounting, or equalizer crosshead guide, fragmentarily showing the equalizer in elevation, and illustrating the yielding and rocking mounting of the equalizer with respect to said guide and thus with relation to the truck frame;

Figure 13 is a sectional view on the line 13-13 of Figure 12; and

Figure 14 is a transverse section taken substantially on the line 14-14 of Figure 12.

Turning now to the general views of the truck, and bearing in mind that the invention is in certain broad aspects not limited to a truck structure, nor specifically to the particular number of wheels and axles or the specific grouping thereof herein shown, it will be seen that the present embodiment of the invention illustrated in these figures, involves a truck frame 15 which extends, in general, longitudinally of the vehicle, in a position to overlie the axles 16, which latter, however, are not directly mounted or journalled in said frame.

The truck frame is preferably a single rigid structure, formed, for example, of sheet metal such as steel or some suitable lighter alloy, and comprising longitudinally extending side trusses 17, 17a (Fig. 3), flanged over to form an upper decking or stiffening, as at 18 (Fig. 2) and integral with, or rigidly secured (as by welding) to cross members 19, 20, 21, 22, and the like, and diagonal members such as 23, 24, which latter form X or V-shaped braces when viewed in plan.

The transverse members 20, 21 and 22 preferably include the top flanges (identified by said numerals), the bottom flanges 20a, 21a, 22a, and deep vertical webs 20b, 21b, 22b. The diagonals 23 and 24, at their point of intersection, are on a level with and merge into the flange 21a; near the center of the truck they are joined together by the horizontal transverse flange 22a welded to the central cross-structure of the frame; and at their opposite ends they are joined by a similar transverse plate 24a, welded to the web 20b. For added stiffness, the diagonal braces 23 and 24 may, in cross-section be upwardly arched or convexed, as indicated by the shading in Fig. 2. The level of the members 23 and 24 and associated parts forming junctures therewith is below

the top of the frame but above the axles, as seen in Fig. 3. The axles and associated parts may thus be readily dropped from their zones A, B, for repairs.

The side trusses and top decking of the frame arrangement above described, it will readily be seen, can in large part be readily shaped or bent from one piece to the form shown, and such parts as are more easily made separately, (for example, various cross and diagonal braces) can be readily welded or otherwise secured to the main portion in order to make a rigid, unified, structure. Such a general arrangement results in, or can be made to form, substantial lightening apertures or openings, as illustrated at 25, 26, 27, and the like 10 (viewed in plan in Figure 2), and at 28, 29, 30, 31, and the like (seen in the side elevational views of Figures 3 and 5). In addition to the upper flanging or decking 18 and the subjacent diagonal bracing, seen in Figure 2, additional 20 flanging or stiffening may be provided, such as at 32, as seen in Figure 5. The frame includes, or has associated with it, certain additional structural members and other features, such as attachment fittings and the like, as will appear 25 more clearly hereinafter.

The frame 15 is carried on the wheels 33 (diagrammatically shown in Figures 3 and 5) which may be equipped with rubber tires 34 and metal flanges 35 (as seen in Figure 1), in the following manner:

Each pair of wheels is mounted upon an axle 16, which may preferably though not necessarily be of light tubular non-rotative type, the wheels being rotatably mounted on the outer ends of the 35 axles and carrying suitable brake drums 36 (diagrammatically shown in Fig. 1); this specific type of wheel, tire, and axle, being not, per se, a part of my present invention. The wheels and axles may desirably be divided into a plurality of groups, preferably two groups; and in the illustrated embodiment each group is made up of two axles with their wheels, one group being located toward one end of the truck frame and the other group being located toward the opposite 45 end thereof. As best seen in Figures 3 and 5, free space or clearance is provided beneath the truck framing, in the general upwardly arched zones A, B and A, B, for the axle mechanism.

The axles of each pair or group are equalized 50 together (separately from those of the other group) by a pair of equalizer members 37, one located at one side of the truck and the other at the opposite side, and each lying between the outside face of the truck and the inner faces of the 55 wheels, each of said equalizers having the combined functions of vertical and lateral equalization. Each equalizer is flexibly connected, at its respective ends, as by spherical joints or ball seats, with the two axles of a pair, as diagrammatically indicated at 38, 38 in Figure 1, so as to provide for relative angling between the equalizers and the axles in a horizontal plane as seen in that figure, for vertical rocking of the individual 60 axles, and for a rotative oscillation of the equalizer about the axis x of the axle, as will be clear from that figure and Figure 5.

In the foregoing manner, the two axles 16, of a pair, are permitted a true lateral motion, relative to each other and to the truck, which, however, is equalized by the members 37, in a manner hereinafter to be described, the equalizers thus further forming with said axles a parallelogram, which is rectangular, viewed in plan, when the truck is on straight track, and which becomes 75

rhomboidal when the truck is on curved track (as in Figure 1). The equalizers thus also maintain the axles in parallelism to each other (viewed in plan) and perpendicular to the longitudinal center line of the truck frame. Likewise,

5 it will now be evident that the members 37 equalize the distribution of the weight upon and the vertical motions of the two axles of a pair, relative to each other and to the truck frame, as occurs when passing over irregularities in the track, and the like. The foregoing will appear still more clearly after the description of the mounting of the equalizers on or in the truck frame, as follows:

10 15 At the side of the truck frame, at a point 39 intermediate the two axles of a pair is mounted a shell, housing, or guide, which may take the form of a tubular or cylindrical member 40, rigidly secured, as by welding, to the truck frame;

20 and the equalizer 37, at an intermediate point, is pivotally mounted therein on a horizontal transverse pivot axis 41, for rocking of the equalizer in a vertical plane, and upon a vertical pivot axis coinciding with the axis 42 of the member 40, for

25 lateral rotation or oscillation of the equalizer, with respect to the truck frame. As will be later described in detail, the equalizer may further be provided with vertical sliding motion within the guiding cylinder 40.

30 It will now be evident that one group or set of wheels with their axles is arranged for both lateral and vertical equalization by a single or common equalizer system, which serves additionally to maintain the axles always in parallelism with

35 each other and with a transverse line through the truck frame, and further serves to position said axles with respect to their location considered longitudinally of the truck frame. The lateral centering, the ultimate limiting of motion,

40 the resilient mounting, and the horizontal and vertical damping of motions and vibrations, of both axles of said pair with respect to the truck frame, are also preferably carried out by this same equalizer system; as will hereinafter appear from

45 consideration of the more detailed figures of the drawings.

However, before proceeding to such details, some additional consideration should be given to Figure 1. From this figure it will be noted that,

50 on a curved track (with a truck having two pairs of axles, so equalized) the end, or outer, axle of each pair will move laterally toward the inside of the curve; and the two inner axles will move toward the outside of the curve; and that under

55 any of these lateral movements, as well as under any movements of the axles, either bodily, or rocking, in vertical planes, the axles of a pair are equalized together; and if there are two such sets or groups, one at each end of the truck

60 frame, these two groups are in turn equalized together by the truck frame 15 itself, and at the same time the central longitudinal line of the truck frame is thereby maintained at substantially true tangency to the curve.

65 In addition to such action on a curve, it will be seen that the effect of all irregularities in both straight and curved track (both of a lateral and of a vertical nature) will be distributed between the guiding wheels of the group and the following wheels thereof.

It should be understood that I may mount the truck on but one group of equalized axles, or upon two groups as shown; that more than two axles might make up each group; or that one end of

70 and the other end by a single pair of wheels (or more than one pair) mounted or journaled in the frame in any of the heretofore known ways; although the arrangement shown is the present preferred embodiment of the invention.

75 Turning now to the detailed features forming parts of, or associated with, the equalizer mechanism: It will be observed from the drawings in general, and particularly by reference to Figures 4, 9, and 10, that the equalizer member 37 is universally mounted upon the axles which it equalizes, by means of a ball 43 externally formed on or secured to each axle, and a spherical seat 44 which may be formed by two annular bearing members 44a and 44b, the assembled ball joint being mounted in an aperture 45 adjacent the end of the equalizer member, and retained in place by a block member 46, which has slot and groove-engagement at 47, 48 with the open jaws 48, 49 of the equalizer head 49, between which jaws the block is held as by a bolt 50.

The equalizer 37, intermediate its ends has a flattened boss 51 transversely apertured at 52, said flat-sided portion 51 fitting between a pair of vertical webs or walls 53 (see Fig. 13) of the plunger or crosshead 54 which is mounted within the housing or cylindrical mounting 40. The equalizer is pivoted in said crosshead, on a horizontal transverse axis, by means of the pivot pin 55, which extends through apertures 56 in the walls 53 and through the aperture 52 in the equalizer. Suitable holes or openings 57 and 58 are provided in the front and rear walls of the crosshead guide 40, for insertion of the pivot pin 55 and the retaining nut 59. It is obvious that this arrangement provides for rocking of the equalizer member 37 in a vertical plane, about the axis of the pivot pin 55, and suitable means of lubrication may be provided, at this point, as by means of the grooving 60.

40 Bodily relative movement vertically between the equalizer 37 and the guide 40 which is fixed on the frame is taken care of by vertical sliding of the crosshead 54 within the bore of the guide member 40; and a spring 61, housed within the chamber 62 formed by the upper portion of the cylindrical shell 40 serves to provide a yielding support of the truck frame upon the equalizer. The cylinder 40 may be a casting, having core and inspection holes *a* and *b*, closed respectively by permanent and removable plates *c* and *d*.

45 Oscillation of the equalizer in a transverse horizontal plane, upon a vertical axis intersecting the axis of the pivot pin 55, is accommodated by virtue of the piston-like ends 63 and 64 of the crosshead 54, which are mounted with a rotating, as well as a vertically sliding, fit in the cylindrically bored parts 65 and 66 of the guide member 40. Lubricant fittings may be applied to the apertures 65a, 66a. All of the movements of the equalizer, as indicated to an exaggerated degree by the lines 37a, 37b and 37c (in Figures 12 and 14) are permitted by the enlarged vertically extending apertures 67 formed in the walls of the crosshead guide 40.

50 The mounting of the equalizer guide member 40 upon the truck frame is rendered secure by means of the ledges or surfaces 40a and 40b (see Figs. 13 and 14) which abut, respectively, against the outer face and lower edge of the frame (as seen in Figs. 2, 3 and 5) and to which said surfaces are preferably welded. I prefer to mount the entire equalizer system outside the plane of the side of the frame and inside the plane of the wheels, as that is most efficient, economical of

weight, and convenient for arrangement of shock absorbers and other parts.

Controlled limitation of the lateral angling of the equalizers (and thus a tendency to center or return the axles and wheels to their normal mid-position) is obtained by means of an extension 68, formed at one end of each equalizer, which abuts, at its inner face (as seen in Fig. 2) against a plunger 69 (as seen in detail in Fig. 11). The plunger fits into the outer end of a cylinder 70 which houses a centering spring 71, reacting between the plunger 69 and a fixed abutment or plate 72. If desired, an inner fixed limit of motion may be provided by abutment of the flange 73 of the plunger against the end 74 of the cylinder 70; and a fixed limitation of the outward movement of the plunger may be obtained by means of the bolt 75, which extends longitudinally through the spring 71 and is secured as by welding 76 to the plunger 69 and retained in place (and if desired, adjusted) by means of a nut 77 bearing against the inner face of the fixed abutment 72.

A pair of these centering units are mounted, one at each end, on a cross member or brace 78 (see Figs. 2, 7, 8 and 11), the centering spring 71 cylinders preferably being integral with the cross-brace, which latter may be made of stock tubing, partially cut away, as shown. The centering assembly, thus formed, may be secured to the frame of the truck in any desired manner, as by means of the brackets or strap members 79, which, as seen in Fig. 3, are secured to the flanging 32 of the frame members 17a.

If desired, a certain amount of "free lateral" may be provided for the equalizers, and thus for the axles, by adjusting the centering units to a point where there is some slight clearance between the inner faces of the equalizer ends 68 and the outer faces of the plungers 69. However, even if the device is arranged or adjusted so that there is no free lateral, (i. e. so that the spring-pressed plungers 69 are against the equalizers when the latter are in their mid-position, that is "neutral" laterally) the adjustment is preferably such that the springs on opposite sides are not both exerting a material compression force upon the two opposite equalizers at the same time, as otherwise their action would simply be opposite and would in large part destroy the intended centering effect.

In addition to lateral centering mechanism, I preferably also employ a lateral cushioning or shock absorbing device, which may be of the double-acting, non-resilient type. As seen in Figure 4, any suitable hydraulic, or other, shock absorber 80 (the details of which need not be here shown) is mounted by a bracket or upstanding plate 81, upon the cross member 19 of the truck frame. The rotative operating member or shaft 82 of this shock absorber may be coupled with an axle 16 by any suitable means such as a lever 83, a link 84 which is pivoted at 85 to the lever, a pivot 86 connecting said link to an arm 87 of a bell crank, a fixed pivot 88 for the bell crank, a ball joint 89 connecting the second arm 90 of the bell crank to a link 91, which latter is adjustable for length by the devices 92, and a pivot or ball joint 93 connecting the link to a bracket 94 which is welded or otherwise securely fastened to the axle 16. By this mechanism, the vibrations and oscillations of the interconnected pair of axles and equalizers are damped or restrained as against the building up of synchronous motions or periodic vibration, laterally of the truck.

I prefer also to damp the vertical motions of the equalizer 37 and thus of the axles, and as seen in Figs. 2, 3, 5 and 10, this is accomplished by means of a pair of shock absorbers 95, each of which may be fixed upon the truck frame. The connection between each such damping device and the equalizer may be by means of the shock absorber shaft 96, the lever 97, a pivot or ball joint 98, link 99, and pivot or ball joint 100, connecting the link to an apertured ear 101 on the equalizer member. Adjustment of the length of the links 99 may be obtained by a threaded device as indicated at 102. The flexible or ball joints in the vertical shock absorber permit free lateral axle play, while those in the lateral shock absorber connections permit free vertical axle play and axle rocking.

By reference now to Figures 2, 3 and 6, it will be seen that the mounting of the main frame of the vehicle upon the truck frame 15 (the mounting of which truck frame on the axles has just been described) provides for an additional resilient support, as well as for swiveling action of the truck, and for a certain amount of lateral or swing-motion in the truck itself.

In Figure 6, a longitudinal member or girder of the vehicle frame is indicated at 103. This member may have a downwardly extending cylindrical portion 104, providing a rotative or swiveling bearing; through the intermediation of the lubricant pad or plate 105, cup-shaped member 106 and pad 107, with the recess or center plate pocket 108 of the truck bolster 109. A center pin extending through these parts is illustrated at 110.

The bolster 109, at its outer ends carries, upon its upper face, a pair of upstanding brackets or supports 111, which serve to mount side bearing guides 112 in which the side bearings or rollers 113 are mounted on inclined or arcuate tracks 112a. These rollers, it will be understood, serve to cooperate with transverse members or transoms of the main frame 103, or with some other part of the vehicle superstructure or frame, not only to support the latter in conjunction with the swivel mounting but also to tend to center the truck frame, about its point of pivotal mounting, with relation to the vehicle proper, the inclined ways 112a co-operating toward this end.

In general, the bolster 109 is of box shape in cross section, provided with strengthening webs 114, 115; and, at the ends, it is provided with spring-band seats or pockets 116, opening downwardly, within which suitable pads or filler blocks 117 may be fitted, against which the upper spring bands 118 bear. Rubbing pads 109a may be positioned between the bolster and the frame, not only to take the wear but also to keep the bolster in its true transverse plane. Full elliptic springs 119 may be provided, (the individual leaves of which are not shown) the lower spring bands 120 of which are seated or recessed into seats in the upper surfaces of the end portions or castings 121 of the tubular spring plank 122.

The said end portions 121 of the spring plank 65 are provided at their lower faces with recesses or seats to receive the yoke of a link member 123, which is substantially U-shape (as seen in Figure 3), the arms of which are connected, as by bolts or other pivot devices 124, to the solid bushings 125a of the laterally extended ends 125 of the central main part of the cross framing of the truck. This particular portion of the framing is reinforced in a horizontal plane (as seen in Figure 2) by the plate or web structure 126, and 75

comprises primarily vertically deep plates or sheets 127 (see Fig. 3), which latter may be made integral with each other and formed to substantially a U-shape by means of the curved bottom portion 128 (as best seen in Figures 3 and 6); and it will be seen that this U-shaped transverse portion of the frame is seated in the main longitudinal structure 17, 17a of the truck frame, and embraced between the immediately adjacent upper webs 17b thereof, and serves to receive the center pin structure and associated weight-transmitting parts.

Between the upper decking 18 of the main frame 15, and the intermediate horizontal web 126 thereof, are a couple of vertical webs 129, in addition to the longitudinal vertical portion 17 (as best seen in Figure 6). A longitudinally extending box-like structure is thus formed, as a part of the truck frame, just above the bolster 109, and at each side of the center pin construction. This general assembly of the truck frame and associated parts is completed by the provision of pads 130, which may be rubber bumpers, mounted in sockets 131 at the outer faces of the upper longitudinal plates 17, in position to serve as yielding stop devices for the lateral motion of the bolster 109, which latter is adapted to engage said stops by means of an upstanding braced bracket 132, which is located on the upper face 20 of the bolster, mid-way between the arms 125 of the transverse structure of the main truck frame.

Other details of the truck mechanism involve: the provision of U-shaped safety bars or hangers 133 (see Fig. 3) at each end of the truck, which 35 are formed by U-bolts, each loosely embracing an axle, and fastened as by nuts 134 to the top platting 18 of the truck frame; and the provision of conveniently located brake rigging brackets 135 and 136, for the mounting of brake levers and 40 the like for operating the brakes 36 (such rigging, however, not per se forming a part of the present invention).

It will now be evident that, considered in a broad way, the major portion of the mechanism 45 might be applied directly to the main frame of a vehicle, for example, by forming the frame 15 of sufficient size and length as to constitute, itself, the ordinary main frame which is rigid with the superstructure of the vehicle; the upper contour of such frame being made to conform to the requirements necessary for directly mounting the superstructure thereon, without the intermediation of the center pin, bolster, and associated parts. However, it will also be seen that the invention 50 is of especial advantage in truck structures, because of the flexibility of construction and operation, the reduction in weight of the trucks and also of the vehicle as a whole, the minimization of the load per axle and thus the load and other stresses on the tires, and the various other advantages which are obtained by the invention.

In amplification of the foregoing, it might be pointed out that a railway vehicle of substantially ordinary passenger carrying capacity, when mounted on two trucks of the type herein disclosed, can be built within an overall weight substantially less than the weight of an ordinary railroad coach of normal standard construction; even though twice as many axles may be employed as compared with such ordinary practice. Similarly, the weight of an eight-wheel truck built in accordance with this invention may readily be brought down to about $\frac{1}{2}$ to $\frac{2}{3}$ of the weight of the ordinary two-axle truck. This is

obviously of great advantage with any type of wheel and tire, but is especially advantageous in the increase in reliability and safety and the reduction in the upkeep of rubber-tired or other resilient-wheeled running gear.

In addition to the foregoing, it should be noted that while the truck frame itself is of a rigid construction and thus not open to the grave objections chargeable against certain flexibly-jointed truck frame structures which have heretofore been proposed (that is, improper tracking or riding qualities, smaller margin of safety, etc.), yet a great degree of flexibility is provided between the truck frame itself and the wheels, and also between the main frame of the vehicle and the wheels, with respect to the required relative motions of various kinds in the horizontal plane as well as in the vertical plane. At the same time, the various motions are properly equalized, controlled, damped, and limited. It should be emphasized also that while the axles and wheels are given a maximum of freedom to accommodate themselves to both the horizontal and vertical irregularities of the track, a minimum of motion and vibration is transmitted to the car body.

There is further provided the proper swiveling motion, in a horizontal plane, between the main frame of the vehicle and the truck frame, by virtue of the center pin mounting of the main frame on the truck bolster, and at the same time the vehicle is steadied laterally by the side bearings, which also are preferably formed to tend toward the centering of the truck with respect to its swiveling action. There is then provided a yielding or spring mounting, for taking the load and shocks, in a vertical plane, by virtue of the springs interposed between the bolster and the spring plank; and some swinging action is permitted by the pivoted links by which the spring plank is carried on the truck frame. Such lateral or swinging motions are yieldingly resisted by the inclination of the links (as seen in Fig. 6) and also yieldingly controlled and limited by means of the buffers between the bolster and the truck frame. Excessive wear, and relative displacement in a direction longitudinally of the truck, between the bolster and the truck frame, are prevented by the interposed bolster rubbing pads.

Proceeding further, the connection between the truck frame and each of the double-acting equalizers combines, in a unified device, provision for a yielding mounting of the truck frame on each equalizer for cushioned vertical movement, a substantially free pivotal mounting for relative rocking movement in a vertical plane, a substantially free pivotal mounting for relative rocking movement in a horizontal plane, and a fixation of the central point of mounting of the equalizer, both laterally, and longitudinally with respect to the truck frame. Finally, the necessary vertical, lateral and rocking motions of the axles relative to the equalizers are provided by virtue of the ball connections; and still further flexibility may be provided by the pneumatic tires interposed between the wheels and the rails. At the same time, the motions of the equalizers and axles, with relation to the truck frame, are damped by the shock absorbers, and controlled and urged toward mid-position by the centering springs. In addition to all of the foregoing, equalization between the two sets or groups of wheels is obtained through the intermediation of the truck frame itself.

It should here be pointed out that the truck

frame is stabilized both laterally and vertically, and is prevented from "cocking" when on curves or irregularities, not only by virtue of the lateral centering springs (acting on the equalizers) and by means of the centering side bearings, but also because of the location of the pivotal mounting of the truck at a point or zone longitudinally offset from the center of equalization of a wheel-group, and by the longitudinal extension of the truck frame from one equalized group of wheels and axles to another axle or axles. Thus various means are provided to stabilize or steady the truck frame so as to prevent it from being whipped or moved about in unison with the equalizer movements; while at the same time preserving great freedom of movement of the equalizers, axles and wheels, and distributing between the wheels the shocks of track irregularities which are severe at high speeds.

20 In operation, the truck structure thus provides excellent guiding, tracking and riding qualities, even at very high speeds, without excessive motions of the car body, and without the building up of resonant or synchronous oscillations or vibrations in the truck or vehicle.

As to the construction in general, and particularly of the truck frame, attention should be called to the fact that a maximum of functions, and a high degree of strength where required, are obtained with a minimum quantity and weight of material, which is advantageously disposed in the form of equalizers which perform a plurality of functions and in the form of a truck frame which is composed of light-weight main decking, diagonally braced, and supported by two light-weight side trusses, of exceptionally deep section, the whole being cross-braced at advantageous points by members adjacent the mounting of the equalizers, and by a deep central transverse member, of generally U-shaped cross section, which serves also to receive or house the bolster, spring plank, and other parts.

I claim:

1. In railway vehicle running gear and supporting structure, the combination of a truck frame, axle means at one end thereof, a set of axles at the other end thereof, a pair of rigid bars equalizing together the axles of said set, both laterally and vertically, means for supporting the vehicle frame upon said truck frame in the middle region of the latter, whereby said truck frame serves as an equalizer device between the axle means at one end and the set of axles at the other end, a set of relatively angled pivot devices interposed between the truck frame and each equalizing bar accommodating vertical and lateral angling of the latter, a vertical guide for each such set of pivots providing for appreciable bodily vertical movement thereof and thus of the associated bar, and a yielding resistance device at each set of pivots accommodating said vertical movement.

2. In a truck structure of the character described, a frame, means for yieldingly supporting a vehicle body thereon, a plurality of axles with their wheels, arranged for relative lateral and vertical motions and for such motions relative to said frame, equalizer mechanism having flexible connections with said axles, pivot means associated with said equalizer mechanism and arranged to provide for vertical and lateral rocking of the same, yielding means for transmitting weight from said frame to said pivot means, and guide means for fixing the pivot locations both laterally and longitudinally with respect to the frame and

providing for guided bodily vertical movement of the equalizer mechanism subject to the restraint of said yielding mechanism.

3. A truck structure comprising: a frame having longitudinally extending side portions lying substantially in vertical planes, central transverse structure intermediate the ends of said side portions for receiving weight of the vehicle, a pair of transverse vertical interbracing members between said side framing, one toward each end of the truck, and diagonal members interbracing said central transverse structure with the juncture formed by the side frame portions and the transverse members; a weight-transmitting mounting device at each of said junctures; 15 a plurality of axles with their wheels; and means for supporting said frame upon said axles comprising a plurality of equalizer members, each member having means serving to journal two axles and having a pivotal support associated 20 with one of the said mounting devices.

4. A railway truck comprising a longitudinally-extending truck frame, a group of axles with their wheels, means for transmitting weight from said frame to said group of axles including equalizer mechanism connected with said axles and having a mounting upon the frame providing freedom for lateral and vertical equalizing motions, a yielding weight-transmitting center-pin mounting on the truck frame at a point longitudinally removed from said group of axles adapted for operative association with the vehicle proper, and axle centering mechanism reacting between the frame and the equalizer mechanism at a point longitudinally removed 30 from the equalizer mounting upon the frame.

5. A railway truck comprising a truck frame, a group of axles with their wheels, a swing-motion yieldingly-mounted bolster carrying a swivelling center pin device for transmitting 40 weight from the vehicle proper to the truck frame, means preventing any appreciable displacement of said bolster from a true transverse plane with respect to the truck frame, means for transmitting weight from said frame to said 45 group of axles including equalizer mechanism connected with said axles and having a mounting upon the frame providing freedom for lateral and vertical equalizing motions, and means tending toward lateral centering of the equalizer mechanism, and thus of the axles, with respect 50 to said frame.

6. A railway vehicle truck structure comprising a longitudinally extended truck frame, a swiveling center bearing for supporting weight of the vehicle thereon and having a lateral-motion mounting on the truck frame, axle and wheel means for supporting the truck frame at each end thereof, the said means for at least one end of the truck comprising a pair of axles, a pair of rigid equalizer members in which the ends of said pair of axles are respectively pivotally mounted, for each of said equalizer members a universal mounting upon said frame between the axles of the pair providing for pivotal equalizer movements both laterally and vertically with respect to the frame, yielding resistance means acting upon the equalizers adjacent an end thereof and yielding means for cushioning the load including a spring support between the equalizer mounting and the truck frame.

7. In a vehicle truck structure, a truck frame, a lateral-motion bolster carrying a center pin for pivoting the truck and transmitting vehicle weight to the truck frame, a plurality of wheeled 7

axles, at least two such axles being arranged for relative vertical and lateral motion, weight transmission mechanism between the frame and said axles, said mechanism comprising equalizing means operatively associated with said two axles to equalize vertical and lateral motion between them and cushion means through which the superimposed weight is transmitted from said frame to the equalizing means, and means acting to stabilize said frame from a zone longitudinally removed from the said equalizing means.

8. In a vehicle structure, a frame, a pair of axles with their wheels for supporting weight imposed by said frame, and a pair of equalizers having angling-joint connection with said axles and each mounted on the frame by two pivot means providing intersecting pivot axes whereby the equalizer is associated with said frame in position to serve commonly as a means to transmit such weight and as a means to equalize lateral motions of said axles, the equalizer mounting including means for maintaining the vertical motions of opposite equalizers at their pivot centers in constant parallelism and for fixing their axes of lateral motion at constant relative spacing.

9. Vehicle supporting apparatus and running gear comprising a weight-carrying frame structure, a plurality of axles with their wheels, weight-transmitting equalizer mechanism including rigid equalizers in which said axles are mounted, means mounting said frame structure on said equalizer mechanism between axles including pivots providing for vertical and lateral equalizing motions and sliding guide means with springs providing for bodily vertical movement of said mechanism relative to the frame structure, and yielding resistive lateral motion controlling means reacting directly between the frame and the equalizer mechanism at a region substantially removed longitudinally from the interconnection of the frame structure and the equalizer mechanism.

10. A truck frame formed in large part of sheet metal and comprising a main decking, apertured for lightness, side trusses similarly apertured, means for mounting and transmitting weight to axle equalizers at each side of the frame and adjacent each end thereof, and cross-bracing adjacent the latter means and extending from one side truss to the other.

11. A truck frame formed in large part of sheet metal and comprising a main decking, apertured for lightness, side trusses similarly apertured, means for mounting and transmitting weight to axle equalizers at each side of the frame and adjacent each end thereof, cross-bracing adjacent the latter means and extending from one side truss to the other, and a central cross-brace of substantial depth in a vertical direction.

12. A truck structure including a truck frame formed in large part of sheet metal and comprising a main decking, apertured for lightness, side trusses similarly apertured, means for mounting and transmitting weight to axle equalizers at each side of the frame and adjacent each end thereof, cross-bracing adjacent the latter means and extending from one side truss to the other, and a hollow central cross-brace of substantial depth in a vertical direction and configured and adapted to house a swing-motion bolster and center pin mounting structure.

13. A truck frame comprising upper decking or stiffening means, side trusses extending lon-

gitudinally, vertically deep transverse elements securing the side trusses together substantially centrally thereof in position to receive between them the center pin and associated weight transmitting parts, and substantially horizontal braces diagonally interconnecting said side trusses and braced by said vertically deep transverse elements.

14. A truck frame comprising upper decking or stiffening means, side trusses extending longitudinally, vertically deep transverse elements securing the side trusses together substantially centrally thereof in position to receive between them the center pin and associated weight transmitting parts, and substantially horizontal braces diagonally interconnecting said side trusses, together with transverse vertical bracing webs longitudinally removed from the center of the truck and bracing also said diagonal members.

15. A truck frame comprising upper decking or stiffening means, side trusses extending longitudinally, vertically deep transverse elements securing the side trusses together substantially centrally thereof in position to receive between them the center pin and associated weight transmitting parts, and substantially horizontal braces diagonally interconnecting said side trusses, together with transverse vertical bracing webs longitudinally removed from the center of the truck, said diagonal braces being located beneath said decking and extending from said webs to said elements.

16. A truck frame comprising upper decking or stiffening means, side trusses extending longitudinally, vertically deep transverse elements securing the side trusses together substantially centrally thereof in position to receive between them the center pin and associated weight transmitting parts, and substantially horizontal braces diagonally interconnecting said side trusses, said side trusses being formed to provide clear axle-receiving zones, and said diagonal braces being vertically spaced apart from said zones.

17. A truck frame comprising upper decking or stiffening means, side trusses extending longitudinally, vertically deep transverse elements securing the side trusses together substantially centrally thereof in position to receive between them the center pin and associated weight transmitting parts, and substantially horizontal braces diagonally interconnecting said side trusses, said side trusses being formed to provide clear axle-receiving zones, and said diagonal braces being vertically spaced apart from said zones, portions of said side trusses extending downwardly in position to be between axles, and means on said portions for receiving and securing an axle mounting assembly.

18. An equalizer system for a pair of axles, comprising an equalizer bar adapted to be associated at each end with an axle for transmitting weight thereto; means for mounting said bar at a point intermediate its ends including pivot mechanism providing for vertical and lateral rocking of said bar, means providing for guided bodily vertical movement of the pivot mechanism and means yieldingly cushioning such movement; and shock absorber means connected to said bar to damp vertical movements thereof.

19. An equalizer system for a pair of axles, comprising an equalizer bar adapted to be associated at each end with an axle for transmitting weight thereto; means for mounting said bar at a point intermediate its ends including pivot mechanism providing for vertical and lateral rocking of said bar, means providing for guided bodily

- vertical movement of the pivot mechanism and means yieldingly cushioning such movement; and a pair of vertically acting shock absorber devices connected respectively adjacent opposite ends of said bar.
5. 20. An equalizer system for a pair of axles, comprising an equalizer bar adapted to be associated at each end with an axle for transmitting weight thereto; means for mounting said bar at a point intermediate its ends including pivot mechanism providing for vertical and lateral rocking of said bar, means providing for guided bodily vertical movement of the pivot mechanism and means yieldingly cushioning such movement; and a pair of vertically acting shock absorber devices connected respectively adjacent opposite ends of said bar, together with joint means in said connections providing substantially free lateral movements of the bar.
10. 21. An equalizer system for a pair of axles, comprising an equalizer bar adapted to be associated at each end with an axle for transmitting weight thereto; means for mounting said bar at a point intermediate its ends including pivot mechanism providing for vertical and lateral rocking of said bar, means providing for guided bodily vertical movement of the pivot mechanism and means yieldingly cushioning such movement; a pair of vertically acting shock absorber devices connected respectively adjacent opposite ends of said bar, together with joint means in said connections providing substantially free lateral movements of the bar; and other mechanism exerting a controlling effect upon lateral rocking equalizer movements.
15. 22. In a railway vehicle truck, a truck frame, a plurality of axles, a pair of equalizers extending between adjacent axles to transmit weight thereto, means articulating said axles to said equalizers for relative angling both vertically and laterally, and pivot mechanism mounting the frame upon each equalizer for relative vertical rocking about a point which is fixed longitudinally of the frame but vertically movable with respect thereto and for relative lateral rotation about an axis which is fixed with respect to the frame.
20. 23. In a railway vehicle truck, a truck frame, a plurality of axles, a pair of equalizers extending between adjacent axles to transmit weight thereto, means articulating said axles to said equalizers for relative angling both vertically and laterally, and pivot mechanism mounting the frame upon each equalizer for relative vertical rocking about a point which is fixed longitudinally of the frame but vertically movable with respect thereto and for relative lateral rotation about an axis which is fixed with respect to the frame, and means tending to maintain a parallel relationship between the equalizers and the longitudinal plane of the truck frame, such means reacting between the equalizer and the frame at a point substantially removed longitudinally from the point of pivoting of the equalizer on the frame.
25. 24. In a railway vehicle truck, a truck frame, a plurality of axles, a pair of equalizers extending between adjacent axles to transmit weight thereto, means articulating said axles to said equalizers for relative angling both vertically and laterally, and pivot mechanism mounting the frame upon each equalizer for relative vertical rocking about a point which is fixed longitudinally of the frame and for relative lateral rotation about an axis which is fixed with respect to the frame and means tending to maintain a parallel relationship between the equalizers and the longitudinal plane of the frame, such means reacting between the equalizers and the frame at a point substantially removed longitudinally from the point of pivoting of the equalizer on the frame.
30. 25. In a railway vehicle truck, a truck frame, a pair of non-rotative axles with wheels rotatably mounted thereon, a pair of rigid equalizers extending from axle to axle to transmit weight thereto, a universally-angling connection between each equalizer and each axle capable of transmitting lateral thrusts as well as weight to the axle, and a universal pivot mounting for each equalizer on the truck frame intermediate the axles of the pair, with cushioned vertically sliding means through which the superimposed weight is transmitted to the equalizers.
35. 26. In a railway vehicle having a main frame, the combination of a truck frame, axle means at one end thereof, a set of axles at the other end thereof, weight transmitting equalizer means pivoted on said truck frame for equalizing the axles of said set both laterally and vertically, the equalizer pivot means being restrained as against lateral motion relative to said truck frame, and a swiveling center bearing adapted to receive weight from said vehicle frame, and transmitting weight through a lateral-motion mounting upon the truck frame.
40. 27. In railway vehicle supporting structure, a plurality of wheeled axles having freedom for relative lateral motion and rocking movements, a weight-carrying frame extending as a rigid unit from adjacent the wheels at one side to adjacent the wheels at the other, at each side of said frame a rigid equalizer member having a lateral-thrust-transmitting connection with each of said axles comprising a ball-joint thereon, and mechanism mounting each equalizer member on the frame at a fixed vertical axis with freedom for vertical and lateral angling and for substantial bodily vertical movement on said fixed axis but preventing appreciable transverse rolling of the equalizer member.
45. 28. In railway vehicle supporting structure, a plurality of wheeled axles having freedom for relative lateral motion and rocking movements, a weight-carrying frame extending as a rigid unit from adjacent the wheels at one side to adjacent the wheels at the other, at each side of said frame a rigid equalizer member having a lateral-thrust-transmitting connection with each of said axles comprising a ball-joint thereon, mechanism mounting each equalizer member on the frame at a fixed vertical axis with freedom for vertical and lateral angling and for substantial bodily vertical movement on said fixed axis but preventing appreciable transverse rolling of the equalizer member, and cushion means transmitting weight from said frame to each equalizer member adjacent its said axis.
50. 29. In railway vehicle supporting structure, a plurality of non-rotative axles with wheels rotatably mounted thereon and having freedom for relative lateral motion and rocking movements, a weight-carrying frame extending as a rigid unit from adjacent the wheels at one side to adjacent the wheels at the other, at each side of said frame a rigid equalizer member having a lateral-thrust-transmitting connection with each of said axles comprising a ball-joint thereon, and mechanism mounting each equalizer member on the frame at a fixed vertical axis with freedom for vertical and lateral angling and for substantial bodily vertical movement on said fixed axis but preventing appreciable transverse rolling of the equalizer member.

30. A railway truck comprising a truck frame, a group of axles with their wheels, a swing-motion yieldingly-mounted bolster carrying a swivelling center pin device for transmitting weight from the vehicle proper to the truck frame, means preventing any appreciable displacement of said bolster from a true transverse plane with respect to the truck frame, means for transmitting weight from said frame to said group of axles including equalizer mechanism connected with said axles and having a mounting upon the frame providing freedom for lateral and vertical equalizing motions, means tending toward lateral centering of the equalizer mechanism, and thus of 15 the axles, with respect to said frame, and means

limiting the lateral swing-motion of said bolster.

31. In a railway vehicle truck, a truck frame, a plurality of axles, a pair of equalizers extending between adjacent axles to transmit weight thereto, means articulating said axles to said equalizers for relative angling both vertically and laterally, pivot mechanism mounting the frame upon each equalizer for relative vertical and lateral oscillation and bodily vertical movement, and including vertical guide means for accommodating said vertical movement and preventing transverse rolling of the plane of the equalizer relative to the truck frame.

WILLIAM E. WOODARD. 15
